UNITED STATES PATENT OFFICE.

JOSEPH B. DRISCOLL, OF CLIFTON FORGE, VIRGINIA.

HEAT REGISTER.

Application filed July 29, 1921. Serial No. 488,417.

To all whom it may concern:

Be it known that I, JOSEPH B. DRISCOLL, a citizen of the United States, and resident of Clifton Forge, in the county of Alleghany and State of Virginia, have invented 5 certain new and useful Improvements in Heat Registers, of which the following is a specification.

This invention relates to heat registers 10 especially adapted for use in connection with the so-called one-pipe furnaces.

As is well known the heat from the one pipe furnace is directed upwardly through a central conduit on top of the furnace and 15 the cool air supplied to the furnace is drawn through an annular chamber surrounding the hot air conduit. However the constant flow of cool air into the said annular chamber creates an objectionable draft in the 20 room from which the cool air is taken and in many cases the flow of the cold air along the floor to the annular cold air receiving chamber is so objectionable that it is impossible to sit near the register and enjoy 25 the heat radiating from the central hot air conveying conduit on top of the furnace.

A further objection to the use of the one pipe furnace is the fact that the hot air from the furnace rises to the upper floors of 30 the house or building within which the furnace is located so that the lower floors are not uniformly heated until the upper floors are thoroughly heated.

Therefore, an important object of this 35 invention is to provide novel means whereby the heat from a pipeless furnace may be discharged into the room in such a manner that the same will not rise to the top or upper portion of the house without first 40 heating the lower floors.

A further object is to provide a register wherein a portion of the heat penetrates the outer wall of the same and uniformly heats the room during the passage of the heat 45 through the register whereby a substantial saving in fuel is brought about.

Further the invention aims to provide novel means whereby the cold air for the furnace may be taken from a room remote 50 from the room into which the heated air discharges. By this arrangement the circulation of air is maintained and the objectionable drafts of cold air in the main room of the house are eliminated.

55 A further object is to provide a heater which is neat in appearance, of highly

simplified construction and cheap to manufacture.

Other objects and advantages of the invention will be apparent during the course 60 of the following description.

In the accompanying drawing forming a part of this application and in which like numerals are employed to designate like parts throughout the same, 65

Figure 1 is a perspective view of the improved heater in use, the view also illustrating the means for taking the cold air from a room other than the room within which the heater is arranged. 70

Figure 2 is a vertical sectional view through the heater applied, the view also illustrating a portion of the hot air furnace. 75

Figure 3 is a horizontal sectional view taken on line 3—3 of Figure 2.

In the drawing wherein for the purpose of illustration is shown a preferred embodiment of the invention the numeral 5 generally designates a pipeless furnace having 80 its upper portion provided with the usual hot air conveying conduit 6 about which is arranged a cold air receiving chamber or passage 7 which transmits the cold air from the room 8 to the furnace to be heated thereby. Ordinarily the heated air passes from the conduit 6 through the register directly 85 into the room and rises to the upper floors of the house without properly heating the lower floor. The cold air about the floor is 90 drawn into the cold air receiving chamber 7 and creates a constant draft which is highly objectionable to those in the room provided with the register. Therefore, I have provided a detachable register 10 to 95 be arranged over the stationary register and the said register 10 includes a base plate 11 which extends over the upper end of the air passage 7 and thereby prevents the cold air from leaving the room and entering the 100 cold air passage 7. The base plate 11 therefore serves as a supporting means for the register 10 and also as a means for closing the upper end of the chamber 7.

As illustrated in Figure 2 a stack 12 extends centrally from the base plate 11 and is aligned with the hot air conduit 6 to receive the heated air from the furnace. The upper end of the stack 12 terminates below a baffle 14 in the nature of a tube having its upper 105 end closed as indicated at 15. The sides of the baffle 14 extend beyond the sides of the 110

- stack 12 and the lower end of the baffle is open so as to permit of the discharge of the heated air adjacent the floor. As the air is directed downwardly by the baffle 14 the 5 lower floor of the house will be heated before the movement of the heated air to the upper floors of the house. The baffle 14 is supported in spaced relation to the stack 12 and in spaced relation to the floor by means of 10 a plurality of radial brackets 18 secured to the stack and having upwardly directed terminal portions 19 which are engaged with the lower end of the baffle 14. The brackets 18 not only serve as a supporting means for 15 the baffle but as a supporting means for a dust absorbing member 20 which is of annular formation and of any desired material. However, the dust excluding member 20 is sufficiently porous to permit of the passage 20 of the heated air through the same. When desired the annular dust collecting member 20 may be removed for the purpose of cleaning the dust picked up from the heated air passing through the same. A further object 25 of the dust collecting member 20 is to uniformly distribute the heated air in the room or more specifically to provide for the uniform discharge of the heated air from the outlet end of the baffle 14.
- 30 In carrying out the invention, one or more pipes 220 are connected to the cold air passage 7 and are also connected with a register 21 fitted in the floor of a room other than the room into which the heated air discharges. This arrangement provides for 35 the constant circulation of air through the house and eliminates the cold draft in the room which is provided with the hot air register.
- 40 In the summer the register 10 may be removed and a rug placed over the register which is permanently embedded in the floor.
- The improved register 10 does not mar the appearance of the room within which 45 the same is arranged and in fact the register may be provided with ornamental fluting or any kind of ornaments.
- In operation the heat is prevented from discharging too rapidly from the register 50 and thereby causes a portion of the heat to penetrate the outer wall of the same. By reason of this construction a substantial saving in fuel is brought about.
- In other words the heat is retarded when 55 passed through the register and a portion is caused to penetrate the wall of the same and thereby uniformly heat the room after the manner in which a stove heats a room.
- Attention is directed to Figure 2 which 60 illustrates that the upper end of the baffle is closed so that the heat is caused to move downwardly and out through the open lower

end of the baffle. It will be seen that the heat is discharged upon the metallic base plate 11 and therefore does not in any way 65 mar the floor surrounding the furnace register. Furthermore by closing the upper end of the baffle the heat is discharged rather close to the floor and consequently 70 does not reach the vicinity of the ceiling as early as it otherwise would.

In summarizing it will be seen that the sole outlet for the heat is at the bottom of the body 10 and this heat is directed onto the base plate 11 which extends a substantial distance beyond the register and consequently overlies the flooring adjacent the register so as to protect the flooring from the heat of the furnace. It will be seen that the closed upper end causes all the heated air which passes through the centrally arranged conduit 12 to pass downwardly out through the lower end of the body 10 and thus the base plate 11 not only forms a supporting means for the heater or register but also as a baffle for the heat and as a means to close the cold air conduit of the one pipe furnace. By so arranging the parts that the base plate performs the three separate and distinct functions enumerated above the utility and usefulness of the register is greatly increased.

I claim:—

1. A register for one pipe furnaces comprising a base plate adapted to extend over and close the upper end of a cold air passage in the stack of a one pipe furnace, said plate being provided with an opening surrounding the upper end of the hot air conduit of the furnace, a stack supported by said base plate, a baffle of tubular formation surrounding said stack and having its upper end closed and arranged in spaced relation to said stack, radial brackets carried by said stack and supporting said baffle, and a dust collecting member carried by said brackets and being porous to permit of the passage of the heated air, said brackets supporting the baffle in spaced relation to the base plate.

2. The combination with a one-pipe furnace having a central hot air passage and an annular cold air passage, of a register having a base plate extending over and closing the cold air passage and having a central opening aligned with the hot air passage whereby the hot air may flow into the room having the register and a cold air pipe connected to the cold air passage and adapted to conduct cold air from another room.

3. A supplemental register for one pipe furnaces comprising a base plate adapted to extend over and close the upper end of the

annular cold air inlet conduit in a one-pipe furnace, a stack mounted on the plate and aligned with the central hot air outlet of the furnace, a baffle receiving the stack and having its upper end closed and its lower end open for the discharge of heat, the open lower end of the baffle being adapted to discharge the heat onto said base plate, said base plate being extended a substantial distance beyond the register of the one-pipe **10** furnace to protect the adjacent flooring from the heat discharged by said baffle, brackets carried by said stack and supporting the baffle in spaced relation to the stack, and a dust collecting member mounted on said **15** brackets and disposed in the path of travel of the heat.

JOSEPH B. DRISCOLL
